EXPANSIBLE LINK CHAIN FOR A BRACELET OR SIMILAR ARTICLE

Karl C. Augenstein, Cranston, R.I.
(% Speidel Corp., 70 Ship St., Providence, R.I.)

Filed Aug. 21, 1959, Ser. No. 57,249

Term of patent 14 years

(Cl. D45—4)

Fig. 1

Fig. 2

Fig. 3

Fig. 4

Fig. 1 is a top plan view of an expansible link chain for a bracelet or similar article showing my new design in contracted position;

Fig. 2 is a top plan view of the expansible link chain shown in Fig. 1 in an expanded position, portions of the conventional appearing bottom links being visible between the expanded top links;

Fig. 3 is an enlarged top plan view of a single top link of the expansible chain; and

Fig. 4 is an edge elevational view looking from right to left at the top link shown in Fig. 3.

The dominant feature of my design resides in an expansible link chain for a bracelet or similar article consisting of a series of rectangular links, the top surfaces of

which are characterized by plane flat end portions and an intermediate rectangular central portion formed with fine engraved ridges extending both longitudinally and transversely of the chain giving the effect of a wide dull band with shiny borders, as shown.

I claim:

The ornamental design for an expansible link chain for a bracelet or similar article, substantially as shown and described.
